TWO-WHEELED FIGURE SKATE

Ralph L. Smith, 1431 Ocean Ave.,
Santa Monica, Calif. 90401

Continuation-in-part of design application Ser. No.
458,196, Apr. 5, 1974. This application May 6,
1974, Ser. No. 467,007

Term of patent 14 years

Int. Cl. D21—02

U.S. Cl. D34—14 C

Fig. 1

Fig. 2

Fig. 3

Fig. 4

FIG. 1 is a top, front and right side perspective view of a two-wheeled figure skate showing my new design;
FIG. 2 is a left side elevational view thereof;
FIG. 3 is a front elevation view thereof; and
FIG. 4 is a bottom plan view thereof.
This application is a continuation-in-part of my application Ser. No. 458,196, filed Apr. 5, 1974.

I claim:

The ornamental design for a two-wheeled figure skate, substantially as shown.
